UNITED STATES PATENT OFFICE.

CYRA B. WATTLES, OF PROVIDENCE, RHODE ISLAND.

FLOOR-DRESSING MACHINE.

No. 817,410.

Specification of Letters Patent.

Patented April 10, 1906.

Application filed July 20, 1903. Serial No. 168,394.

To all whom it may concern:

Be it known that I, CYRA B. WATTLES, a citizen of the United States, residing at Providence, in the county of Providence and State 5 of Rhode Island, have invented a new and useful improvement in Floor-Dressing Machines, of which the following is a specification.

This invention has reference to an improvement in floor-dressing machines, and more particularly to an improvement in the means for stopping the operation of the machine by lifting the dressing-roller from the floor.

15 In floor-dressing machines as heretofore constructed the shaft of the dressing-roller is usually connected by a flexible shaft to an electric motor, and the dressing-roller is controlled through the motor. By this construction the operator is obliged to stop the motor when it is required to stop the operation of the dressing-roller on the floor for a short time.

The object of my invention is to stop the 25 operation of the dressing-roller when required without stopping the motor, and I accomplish this object by constructing a floor-dressing machine with means for lifting the dressing-roller from the floor when the handle 30 of the machine is lowered and to bring the dressing-roller into engagement with the floor when the handle is raised by the operator into the position for operating the machine.

35 My invention consists in the peculiar and novel construction of a floor-dressing machine having cross-bars extending through the frame of the machine near the dressing-roller to engage with the floor and act as a 40 fulcrum to lift the dressing-roller from the floor when required by depressing the handle of the machine, as will be more fully set forth hereinafter.

Figure 1 is a front view of my improved 45 floor-dressing machine, showing the machine connected to an electric motor by a shaft with universal joints; and Fig. 2 is a side view of the floor-dressing machine, showing the machine in its operative position in full 50 lines and in its inoperative position with the dressing-roller raised from the floor in broken lines.

In the drawings, *a* represents an electric motor, and *b* the floor-dressing machine. The 55 motor *a* derives its power from a source of electric energy through the wires in the flexi-

ble cable *a'*, connected with the motor, and it is supported on the casters *a²* *a³*, pivotally secured in the brackets *a⁴* *a⁵*, so that the motor may be readily moved on the floor. On the 60 end of the armature-shaft *a⁶* is the universal joint *a⁷*, connecting with the shaft *a⁸*, which in turn is connected with the shaft of the dressing-roller by the universal joint *a⁹*.

The floor-dressing machine *b* consists of the 65 frame *b¹*, having the arms *b²* *b³* with the bearings *b⁴* *b⁵*, the T-shape handle *b⁶*, the cross-bars *b⁷* *b⁸*, carried through the frame *b¹* an equal distance on each side and secured in the frame in any well-known way, and the 70 dressing-roller *b⁹*, secured on the shaft *b¹⁰* in the bearings *b¹¹* *b¹²*. The dressing-roller *b⁹* consists of a cylindrical body of metal covered with a sheet of abrasive material, such as sandpaper, and, deriving its power from the 75 motor *a* through the shaft *a⁸* and the universal joints *a⁷* and *a⁹*, is revolved on the floor at a high rate of speed, while the operator moves it on the floor by the handle *b⁶*. When it is required to stop the operation of the 80 dressing-roller on the floor, the operator depresses the handle *b⁶*. The ends of the cross-bars *b⁷* *b⁸* engage with the floor and acting as a fulcrum the dressing-roller is lifted from the floor, as shown in broken lines in Fig. 2. 85

By the use of my improved floor-dressing machine the operation of dressing a floor is simplified and the operation of the dressing-roller on the floor is stopped when desired without stopping the motor. 90

It is evident that any kind of a motor and flexible shaft connecting the motor with the floor-dressing machine could be used without materially affecting the spirit of my invention.

Having thus described my invention, I claim as new and desire to secure by Letters Patent— 95

1. In a floor-dressing machine, a dressing-roller covered with an abrasive or polishing material rotatably mounted in a frame having two arms for supporting the roller, a motor connected to the dressing-roller by a flexible shaft to rotate the dressing-roller, a handle to the frame and cross-bars in the frame, intermediate the dressing-roller and the handle, acting as a fulcrum on the floor to lift the dressing-roller by depressing the handle and stop the operation of the dressing-roller on the floor without stopping the motor, as described. 100
2. In a floor-dressing machine, the combi- 110

nation with a motor and a flexible shaft, of the frame b' having the arms b^2 b^3 with the bearings b^3 b^3 , the T-shape handle b^4 , the cross-bars b^5 b^6 and the dressing-roller b^9 set 5 cured on the shaft b^7 connected to the flexible shaft and rotating in the bearings b^3 b^3 , all for the purpose as described.

In testimony whereof I have signed my name to this specification in the presence of two subscribing witnesses.

CYRA B. WATTLES
